[57] CLAIM

The ornamental design for a torch or similar article, substantially as shown and described.

DESCRIPTION

FIG. 1 is a front elevation of a torch or similar article embodying my new design;

FIG. 2 is a rear elevation thereof;

FIG. 3 is a side elevation thereof;

FIG. 4 is an elevation of the opposite side thereof;

FIG. 5 is a view of the side shown in FIG. 4, but with the control lever retracted into the casing;

FIGS. 6 and 7 are respectively top and bottom plan views of the torch with the control lever pulled out from the casing.
